**BREAK BACK TOOL USED IN CONCRETE
CONSTRUCTION WORK**

Theodore A. Kus, Oak Lawn, Ill., assignor to Universal
Form Clamp Co., Chicago, Ill., a corporation of Illinois

Filed Oct. 30, 1961, Ser. No. 67,300

Term of patent 14 years
(Cl. D54—13)

FIGURE 1 is a perspective view of a break back tool used in concrete construction work showing my new design;

FIGURE 2 is a side elevational view;

FIGURE 3 is a top plan view;

FIGURE 4 is a front elevational view; and

FIGURE 5 is a rear elevational view thereof.

The characteristic feature of my design resides in the particular configuration of the head portion merging with the handle, as best shown in FIGURE 2, and including the bifurcated end portion disposed at a right angle to the axis of the tool handle.

I claim:

The ornamental design for a brake back tool used in concrete construction work, substantially as shown and described.
